UNITED STATES PATENT OFFICE.

EDWIN W. SEEGER, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR CONTROLLER.

Application filed June 30, 1922. Serial No. 571,887.

This invention relates to motor controllers and more particularly to starting controllers for synchronous motors.

The invention has among its objects to provide a starting controller for synchronous motors adapted to automatically interrupt the starting connections for the motor and establish running connections therefor under given conditions in the field circuit of the 10 motor.

Various other objects and advantages of the invention will hereinafter appear.

The accompanying drawing illustrates an embodiment of the invention which will now 15 be described, it being understood that the embodiment illustrated may be modified without departing from the scope of the appended claims.

In the drawing,

20 Figure 1 diagrammatically illustrates a controller embodying the invention; and

Fig. 2 is a side elevational view of one of the switches shown in Fig. 1.

Referring to Fig. 1 the same illustrates a 25 synchronous motor having an armature A and field F and a controller for said motor including a 5-pole electromagnetic switch 1 for establishing starting connections therefor through compensator windings 2 and 3, 30 a 3-pole electromagnetic switch 4 for establishing running connections therefor and a field control switch 5. Switch 5 is provided with normally open contact arms 5^a and 5^b for connecting the field F of the motor to a 35 suitable source of direct current such as the battery B through a regulating resistance R, and a normally closed contact arm 5^c for connecting a reactance L across the terminals of said field.

40 The control means for the aforescribed switches includes normally closed electromagnetic relays 6 and 7 having their operating windings connected in parallel across the terminals of reactance L, and electromagnetic switches 8 and 9. Switch 8 is of the double-pole type and is controlled from a push button station including a normally closed push button switch 10 and normally open push button switch 11 and switch 9 is 45 also of the double-pole type and is provided with an auxiliary contact 9^a adapted to normally bridge contacts 9^b and to move into engagement with contacts 9^c. The control means further includes an auxiliary contact 55 member 1^a associated with switch 1 and

adapted to engage contacts 1^b, said contact member being normally out of engagement with said contacts and being adapted upon closure of switch 1 to engage the same. However, as shown in Fig. 2, the several contact arms of switch 1 are yieldingly mounted upon a supporting member 1^c while contact member 1^a is fixed to said supporting member and the arrangement is such that during closure of said switch said supporting member first moves the several contact arms into closed position and thereafter moves with respect to said arms to bring contact 1^b into engagement with its respective contacts.

The function and operation of the controller will now be more fully set forth. Closure of push button switch 11 establishes an energizing circuit for switch 8 through push button switch 10 and said switch in responding maintains itself and establishes an energizing circuit for starting switch 1 through contacts 9^b. Closure of starting switch 1 establishes reduced voltage power connections from lines 1', 1^a and 1^b to armature A of the motor through compensator windings 2 and 3 and the motor then starts up as an induction motor, the field thereof being connected in a closed loop through reactance L. Immediately upon establishment of the starting connections and prior to engagement of contact 1^a with contacts 1^b relay 6 and also relay 7 are energized by the current induced in the field circuit of the motor.

As is well known the current in the short-circuited field of the synchronous motor is 90 practically constant during the starting period for all speeds of the motor from rest to nearly synchronism but the frequency of this current is equal to the line frequency when the rotating field is stationary and reaches zero when the rotating field is brought up to synchronous speed. Also as is well known with a constant current across the terminals of reactance L the voltage across such terminals will vary directly with the frequency 95 of the current. Thus this voltage is relatively high during starting of the motor and approaches zero as the speed of the motor approaches synchronism. Relays 6 and 7 are calibrated so that both of the same are 100 adapted to open upon establishment of the starting connections and the former is adapted to close when the frequency of the current in the field circuit is such that it is 105 proper to establish running connections for

the motor while the latter is adapted to close when the speed of the motor approaches synchronism.

In closing relay 6 establishes an energizing circuit for switch 9 through contact member 1^a and contacts 1^b and said switch in responding maintains itself in closed position. Upon closure of switch 9 the energizing circuit of starting switch 1 is interrupted by disengagement of contact member 9^a from contacts 9^b and running switch 4 is energized by engagement of said contact member with contacts 9^c. As soon as the motor approaches synchronous speed relay 7 closes and establishes an energizing circuit for field switch 5. In responding switch 5 connects the field F across battery B and excludes reactance L from the field circuit. Opening of push button 10 interrupts the energizing circuit of switch 8 and said switch in opening de-energizes running switch 4 and field switch 5 for stopping of the motor.

The starting and running connections for the armature of the motor and field connections therefor are apparent from the drawing. However, the control circuits are not so apparent and the same will now be more fully described. Closure of switch 11 establishes an energizing circuit for switch 8 extending from the lower terminal of a transformer T connected across lines 1' and 1² by conductors 12 and 13 through push button switch 11 by conductor 14 through push button switch 10 by conductor 15 through the operating winding of switch 8 and by conductors 16 and 17 to the upper terminal of said transformer. Upon release of push button switch 11 switch 8 maintains itself by a circuit extending from the lower terminal of transformer T, by conductor 12 through the left hand pole of switch 8 by conductors 18 and 14 through push button switch 10 and through the operating winding to the upper terminal of said transformer as already traced. Closure of switch 8 energizes starting switch 1 by a circuit extending from the lower terminal of transformer T by conductors 12 and 19 through the right hand pole of said switch by conductor 20 through the operating winding of switch 1 by conductor 21 through the contacts 9^b and by conductors 22 and 17 to the upper terminal of said transformer. Upon closure of auxiliary contact 1^a of switch 1 and relay 6, switch 9 is energized by a circuit extending from lower terminal of transformer T through the right hand pole of switch 8 as already traced by conductors 20 and 23 through the operating winding of switch 9 by conductor 24 through relay 6 by conductor 25 through contacts 1^b and bridging contact 1^a and by conductors 26 and 17 to the upper terminal of said transformer. Switch 9 in closing maintains itself by a circuit extending from the lower terminal of transformer T through

the operating winding of said switch as already traced by conductor 27 through the right hand pole thereof by conductor 28 through the left hand pole thereof and by conductors 29 and 17 to the upper terminal 70 of said transformer. Upon closure of switch 9 running switch 4 is energized by a circuit extending from the lower terminal of transformer T through the right hand pole of switch 8 by conductors 20, 23 and 30 through the operating winding of switch 4 by conductor 31 through contacts 9^c and bridging contact 9^a and by conductors 22 and 17 to the upper terminal of transformer T. Upon closure of relay 7, the energizing circuit 80 for switch 5 extends from the lower terminal of transformer T through the right hand pole of switch 8 by conductors 20 and 32 through the operating winding of switch 5 by conductor 33 through relay 7 by conductors 34 and 28 through the left hand pole of switch 9 and by conductors 29 and 17 to the upper terminal of said transformer.

What I claim as new and desire to secure by Letters Patent is:

1. The combination with a synchronous motor, of means comprising electro-responsive switches for establishing starting and running power connections therefor, control means for said switches insuring establishment of said starting connections prior to establishment of said running connections and establishment of running connections upon interruption of starting connections, said means including a normally closed electro-responsive relay to be included in the field circuit of said motor and a reactance to be included in the field circuit of said motor to render said relay responsive to a given voltage which is a function of the speed of said motor.

2. The combination with a synchronous motor, of means comprising electro-responsive switches for establishing reduced voltage armature connections for starting and full voltage armature connections for running, an electro-responsive switch for connecting the motor field to a source of direct current, and control means for the aforesaid switches including a plurality of electro-magnetic timing relays included in the field circuit of said motor during starting and subjected to voltage which is a function of the speed of said motor, one of said relays controlling said first mentioned switches and the other controlling said last mentioned switch.

3. The combination with a synchronous motor, of means comprising electro-responsive switches for establishing reduced voltage armature connections for starting and high voltage armature connections for running, an electro-responsive switch for connecting the motor field to a source of direct current, a reactance normally included

in the field circuit of said motor by said latter switch and control means for said switches including a plurality of electro-magnetic relays each having its operating 5 winding connected in shunt with said reactance, one of said relays insuring establishment of said running connections and interruption of said starting connections upon a given speed of said motor and the other insuring closure of said field switch when the speed of said motor approaches synchronism.

In witness whereof, I have hereunto subscribed my name.

EDWIN W. SEEGER.
